UNITED STATES PATENT OFFICE.

ELMER FARMER, OF BRADDOCK, PENNSYLVANIA, ASSIGNOR TO THE AMERICAN STEEL & WIRE COMPANY, A CORPORATION OF NEW JERSEY.

CROSS-HEAD AND PITMAN CONNECTION.

SPECIFICATION forming part of Letters Patent No. 743,701, dated November 10, 1903.

Application filed May 4, 1903. Serial No. 155,464. (No model.)

To all whom it may concern:

Be it known that I, ELMER FARMER, of Brad-
dock, Allegheny county, Pennsylvania, have
invented a new and useful Cross-Head and
Pitman Connection, of which the following is
a full, clear, and exact description, reference
being had to the accompanying drawings,
forming part of this specification, in which—

Figure 1 illustrates in side elevation a cross-
head and pitman connection constructed in
accordance with my invention. Fig. 2 is a
vertical cross-section on the line II II of Fig.
1. Fig. 3 is a top plan view, and Fig. 4 is a
longitudinal section on the line IV IV of
Fig. 1.

My invention has been especially designed
for use in connection with such machines as
wire-nail machines, in which the wear of the
bearing between the pitman and the cross-
head of the upsetting device has been very
severe and in the constructions heretofore
employed has resulted in the rapid destruc-
tion of the parts. This has been a matter of
serious consequence, necessitating the mak-
ing of frequent repairs and replacement of
the parts of the machine, all of which entail
expense and delay.

In the accompanying drawings, 2 represents
a reciprocating cross-head, and 3 is a pitman
having a yoke 3' for the reception of an ordi-
nary crank, by which the pitman is recipro-
cated. At the inner end of the pitman and
preferably integral therewith is a rounded
bearing portion 4, and the shank of the pit-
man between the bearing portion 4 and the
yoke is formed with a transverse slot 5.

6 is a bearing brass or block, which is set
in a forked recess 2' at the rear end of the
cross-head and may be secured therein by
suitable means, such as a pin or screw. It
receives and serves as a bearing for the bear-
ing portion 4. In the slot 5, back of the bear-
ing portion 4 and fitting against the same, I
set a detachable bearing brass or block 7,

which fits between the walls of the recess 2' 45
of the cross-head. It is held in place by a
key 8, which passes through opposite holes
in the forked end of the cross-head and ex-
tends through the slot in the pitman. The
key 8 may be held against longitudinal mo- 50
tion by set-screws 9. It will thus be seen that
the bearings 6 and 7 are held in the cross-
head with great security, but that in the event
of wear the loose motion may be taken up
merely by interposing liners between the key 55
and the brass 7. When the wear is sufficient
to necessitate replacement of the brasses, the
latter can be removed by detaching the key
8, and they can then be replaced with new
brasses, which are secured by the key in like 60
manner.

Within the scope of my invention as de-
fined in the claims parts of my improvement
may be modified.

I claim—

1. A pitman connection comprising in com-
bination with the pitman and its end bear-
ing, a part to which the pitman is pivotally
coupled, a bearing-block attached to said
part, a second bearing-block fitted in a slot 70
in the pitman, and a key passing through
said slot and connected to the part with which
the pitman is coupled; substantially as de-
scribed.

2. A pitman connection comprising in com- 75
bination with the pitman, a part to which the
pitman is pivotally connected, a bearing-block
fitted in a slot in the pitman, and a key pass-
ing through the slot and connected to the
part with which the pitman is pivotally con- 80
nected, said pitman having a bearing at the
end with said part; substantially as described.

In testimony whereof I have hereunto set
my hand.

ELMER FARMER.
